UNITED STATES PATENT OFFICE.

GIOVANNI AGNELLI, OF TURIN, ITALY.

AUTOMATIC FIREARM.

1,187,957.

Specification of Letters Patent. Patented June 20, 1916.

Application filed February 17, 1914. Serial No. 819,226.

To all whom it may concern:

Be it known that I, GIOVANNI AGNELLI, a subject of the King of Italy, residing at Via Burdin 38, Turin, in the Kingdom of Italy, have invented certain new and useful Improvements in Automatic Firearms, of which the following is a specification.

In automatic firearms such as rifles, pistols and the like with a breech bolt displaceable longitudinally and circularly and having a head provided with wings, closing is obtained at the moment of firing by these wings being brought into contact with counter wings located at the rear portion of the 15 barrel or with an extension which is integral with the barrel of the weapon.

The present invention relates to improvements in this class of firearms, these improvements having for their object to press 20 the breech bolt forward after the recoil and to produce its rotation mechanically in order to effect complete closing.

In accordance with the invention, the possibility, of the weapon being fired at the 25 moment of closing is also avoided and firing is effected by means of a hammer which strikes the firing pin when the trigger is pressed.

The invention is illustrated by way of example, in the accompanying drawing, in which:—

Figure 1 is a longitudinal sectional view embodying the features of the present invention, the parts being shown in the positions 35 assumed at the moment of closing the breech. Fig. 2 is a bottom plan view thereof. Fig. 3 is a view similar to Fig. 1, showing the parts in firing position. Fig. 4 is a bottom plan view of Fig. 3. Fig. 5 is a 40 longitudinal sectional view showing the position of the parts at the end of the recoil. Fig. 6 is a bottom plan view of Fig. 5. Figs. 7 to 12, inclusive, are views similar to Figs. 1 to 6, inclusive, and showing other embodiment of the invention.

The breech bolt O is cylindrical and provided with wings a and with a lever I and carries inside it a cylindrical hollow firing pin P inside which is also housed a spiral 50 spring M which acts merely as a recuperator spring and not as a firing spring.

The obturator runs in the frame c¹ or receiver which is provided with a groove or channel g intended to guide the case z of

the firing pin P in a constantly rectilineal 55 direction. A tooth s round or parallelepiped in form slides in this base; the front portion of this tooth is limited by a helicoidal surface which bears upon the helicoidal face e formed in the body of the breech bolt closure 60 itself. A spring m presses the tooth forward and a pin c passing through a small slot d in the tooth, limits the travel of this tooth. When the tooth occupies its extreme rearward position, its front edge is on a level 65 with the front face of the base while the rear face bears upon the bottom of the base itself.

Fig. 1 represents the mechanism at the moment of closing the breech bolt closure. 70 The firing pin P under the influence of the spring M causes the breech bolt closure O to advance and when the latter has reached the end of its travel, the wings a lodge behind the counter wings of the barrel, the 75 front face of the tooth s ending in a helicoidal surface, presses upon the helicoidal face e of the breech-bolt causing it to rotate completely through the angle corresponding to the width of the slot and thus effecting 80 its complete closing. In this position, the point p of the firing pin remains concealed in the hollow head of the breech bolt closure, because the firing pin is retained by the action of the spring m.

The hammer K which is able to rotate about the pivot q applied to the fixed portion of the weapon, is held in cocked position by a sear, not shown, engaging a notch t of the hub of the hammer.

Assuming that the hammer is caused to fall by acting upon the trigger, the hammer will overcome the counter action of the spring m as shown in Figs. 3 and 4 and will compress it in causing the firing pin to advance until its point projects from the head of the breech bolt closure and in striking upon the cap fires the weapon. Finally assuming that by means of a known automatic system the breech bolt closure is caused to 100 rotate inversely, then, as shown in Figs. 5 and 6 the breech bolt closure in rotating will cause the firing pin to recede by the action of its helicoidal surface which will press upon the tooth s and upon the rear wall of 105 the base z and consequently the breech bolt closure and the striker will recede together maintaining their distance unaltered (as is

the case in ordinary military rifles) and the firing pin will press the hammer down rearwardly bringing it into the cocked position.

The breech bolt and the firing pin after having receded again advance under the influence of the recuperator spring M and the phases described above are repeated in succession. In this form of mechanism, the firing pin is not stopped during the whole of its forward travel by any trigger lever or other obstacle but serves solely as means for transmitting the thrust of the recuperator spring to the breech bolt closure and cause it to advance and to rotate in order to produce the closing. The firing pin is thus retained between the two counter springs M and m and it is only the percussion of the hammer which, in striking it in its rear portion, transmits the blow to the point of the firing pin and consequently to the cap of the cartridge.

The hammer K described above may be replaced by a cylindrical hammer pressed parallel with the axis of the weapon or obliquely thereto by a special spring or by some other known means forming no part of the present invention.

In Figs. 7 to 12, which illustrate another embodiment of the invention, the breech closure is not modified.

The firing pin P carries a fixed base z whose front face is helicoidal in form and contacts with the helicoidal face of the breech bolt. The hub of the hammer carries a projection r.

A stop device b is pivoted at v and is pressed upwardly by a spring n so as to bring the stop b in front of the part z so as to normally hold the firing pin retracted within the breech-bolt. This stop device b is provided with a trip h which lies in the path of the projection r on the hub of the hammer and is depressed thereby so as to withdraw the stop b from the part z just prior to the striking of the hammer h against the rear end of the firing pin.

When at the end of the recoil, the breech bolt and the firing pin again move forward together under the influence of the recuperator spring M, the firing pin is stopped by the nose b of the sear h; during the same period the breech bolt has commenced to rotate and its wings have already come into contact with the counter wings on the barrel; as a result of the impulse communicated to it, the breech bolt completes its rotation, although during the latter portion thereof it is not retained by the pressure of the firing pin; it should however, be noted that the breech bolt is only able to rotate through a small angle as otherwise it would strike against the front face of the base z of the firing pin.

By means of a suitable device which is not here described, the complete rotation of

the breech bolt and its stoppage in its final position might be insured.

If the hammer be depressed under similar conditions, it will accomplish a fraction of a forward rotation and by means of the projection r, will depress the sear b and release the firing pin which will complete its travel and cause the breech bolt to rotate completely; immediately afterward the hammer in descending will produce firing.

Fig. 7 represents the mechanism at the moment of the complete advance of the breech bolt and the stoppage of the firing pin at the end of its travel at 1 or 2 mm. behind the head of the breech bolt.

Fig. 8 represents the breech bolt and the firing pin as viewed from below at the moment of operation described.

Fig. 9 shows the mechanism at the moment of firing; the sear b in descending has released the firing pin which under the thrust of the hammer, advances so that its point projects beyond the breech bolt in such a manner as to fire the weapon.

Fig. 10 represents the breech bolt and the firing pin as viewed from below at this point in the operation.

Fig. 11 represents the breech bolt in its rotated position which causes the firing pin to recede in such a manner that the hammer commences to be pressed rearward.

Fig. 12 is an underneath view of the breech bolt and of the firing pin at this point in the operation.

What I claim and desire to secure by Letters Patent of the United States is:—

1. A firing device for firearms, comprising a rotatable and endwise movable breech-bolt, a non-rotatable and endwise movable firing pin within the breech-bolt, the breech-bolt having a longitudinal opening therein, the firing pin having a guide projection working in said opening and adapted to engage a guideway in a stationary part of the firearm, and means coöperating with the projecting portion of the firing pin to hold the same retracted within the breech-bolt.

2. A firing device for firearms, comprising a rotatable and endwise movable breech-bolt, a non-rotatable and endwise movable firing pin within the breech-bolt, the breech-bolt having a longitudinal opening therein, the firing pin having a guide projection working in said opening and adapted to engage a guideway in a stationary part of the firearm, means coöperating with the projecting portion of the firing pin to hold the same retracted within the breech-bolt, and a hammer coöperating with the projecting portion of the firing pin.

3. A firing device for firearms, comprising a rotatable and endwise movable hollow breech-bolt, a non-rotatable and endwise movable firing pin within the breech-bolt,

a recuperator spring acting on the firing pin to bring the device to normal position after recoil, and means to normally hold the firing pin retracted within the breech-bolt and to permit of the firing pin being driven forwardly in the breech-bolt for firing purposes.

In testimony whereof I affix my signature in presence of two witnesses.

GIOVANNI AGNELLI.
